Stanislaw D. Degorski, 2910 Oliver Road, and Vincent T. Borka, 332 E. Parent, both of Royal Oak, Mich.
Filed Nov. 28, 1961, Ser. No. 155,284
3 Claims. (Cl. 40—104)

This invention relates to a page turner for turning the pages of books, magazines and the like, and more particularly to a page turning device automatically operable to turn a single page upon the actuation of a switch mechanism which may be conveniently operated by foot.

It has long been a problem for musicians to turn the pages of a music book while in the act of playing a musical instrument because the majority of musical instruments require the use of both hands. Various techniques are used by musicians to turn the pages of music books without materially disturbing the continuity of the music. However, none of the techniques has proven entirely satisfactory and the page turning problem has not heretofore been adequately solved. In addition to musicians, others, particularly the physically handicapped, have a need for a device to automatically turn the pages of a book or a magazine. This problem has been solved by the present invention by the provision of a page turner which is efficient in operation and relatively inexpensive.

It is an object of the invention to provide an electrically operated page turner which will turn the pages of a book one by one upon the actuation of a simple switching mechanism.

Another object of the invention is to provide a page turner having a unique mechanism for loading the pages which are to be turned.

A further object of the invention is to provide a support for a book or magazine which is adjustable to receive books or magazines of different sizes.

A still further object of the invention is to provide a page turner in which a page which has already been automatically turned may be manually turned back if desired and whereupon on the next succeeding page turning operation two pages will be turned at the same time.

Another object of the invention is to provide a page turner which will not damage the pages of the book being acted upon.

A yet further object of the invention is to provide a page turner having a novel control for an electric motor which permits the utilization of an inexpensive motor and yet will exactly restrict the motor to turning only a page at a time.

Another object of the invention is to provide a page turning device which may be positioned in any desired angular relationship with the horizontal plane.

A further object of the invention is to provide a page turning mechanism which is relatively fool-proof in operation and which is inexpensive to manufacture and durable in use.

Other objects of this invention will appear in the following description and appended claims, reference being had to the accompanying drawings forming a part of this specification wherein like reference characters designate corresponding parts in the several views.

In the drawings:

FIGURE 1 is a perspective view of one embodiment of the page turner of the present invention;

FIGURE 2 is a perspective view of the page turner of FIGURE 1 showing a book mounted thereon and the beginning of a page turning operation;

FIGURE 3 is a perspective view similar to FIGURE 2 illustrating a further point in the page turning operation;

FIGURE 4 is a sectional view of the page loading

2

mechanism taken substantially along the line 4—4 of FIGURE 2 looking in the direction of the arrows;

FIGURE 5 is a schematic view of the electrical control system utilized with the page turner of FIGURE 1;

FIGURE 6 is a top plan view of the drive system for the device taken substantially along the line 6—6 of FIGURE 1 looking in the direction of the arrows; and

FIGURE 7 is a perspective view of the control structure utilized to limit operation of the device to turning one page at a time.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to FIGURE 1, it will be seen that the page turner 10 includes a book support 12 upon which is mounted an adjustable book stop 14 and a fixed book stop 16. A U-shaped casing 18 is mounted on the support 12 and has mounted therein power means to drive a page loading structure 20 and a page turning arm 22.

The book support 12 is a wire structure the various elements of which are welded or brazed together. The support 12 comprises side wire elements 24, 26 which are bent downwardly at their ends to form supporting legs 28, 30. The legs are joined together by elements 32, 34. The legs 28, 30 serve to raise the book support from the supporting surface on which it is placed and to provide space for mounting the casing 18 beneath the level of the supported book. As will be noted, the leg 28 is shorter than the leg 30, thus supporting the book at an angle to the reader to facilitate easy reading. It will, of course, be appreciated that the book support may be positioned at any desired angle with respect to the horizontal, from a substantially upright position to a substantially parallel position with respect to the supporting surface.

End elements 36, 38 are provided at the juncture of the legs 28, 30 and side elements 24, 26. A pair of parallel elements 40, 42 extend between the end elements 36, 38 and a structural support element 44 extends between elements 40, 42 intermediate the ends thereof. The rearward ends of the elements 40, 42 are raised upwardly a short distance from the level of side elements 24, 26 and have downwardly turned portions 46, 48 which are secured to end elements 34, 36. The elements 40, 42 are raised slightly upwardly so that the two halves of a book may be angled downwardly and be supported on the side elements 24, 26. This slight downward angle is desirable because it permits the pages to lie relatively flat with respect to the plane of the support.

The fixed stop 16 comprises an angle member, one leg 50 of which is secured to the elements 40, 42 while the other leg 52 extends upwardly to abut against one end of a book. The stop 16 serves to locate a book with respect to the page loading mechanism 20 and page turning arm 22.

The adjustable stop 14 comprises a plate 54 having upwardly extending stop members 56, 58, 60. The plate 54 is mounted for sliding on elements 40, 42 by means of clamping plates 62, 64 mounted on the underside thereof and having upturned end portions for frictional engagement with the elements 40, 42. The plates 62, 64 are secured to plate 54 by a screw 66 which is adjustable to permit varying the force necessary to slide the stop. A book clamping structure is provided on the adjustable stop to permit clamping of the pages of a book against the

plate 54. The pages which are clamped are those which are not to be turned during operation of the device. The clamping structure comprises a pair of spring arms 68, 70 which are secured at one end between the plate 54 and clamping plate 64. The arms 68, 70 extend laterally and are formed with an angle so that they will tend to spring downwardly towards the plate 54. The ends of the arms 68, 70 are bent to form generally rectangular clamping feet 72, 74 which extend through the openings between stops 56, 58, 60 to normally lie against the plate 54. Upwardly extending portions 76, 78, terminating in finger engageable elements 80, 82 are provided to permit manual raising of the feet 72, 74 for the insertion of a portion of a book thereunder as best illustrated in FIGURE 3.

In mounting a book on the support 12, the book is placed in open position on the support with the center of the book resting between elements 40, 42. One end of the book is abutted against the fixed stop 16. The adjustable stop 14 is then moved into engagement with the other end of the book. The clamp feet 72, 74 are then raised and clamped onto the pages of the book which are not to be turned.

Considering next the page loading mechanism 20, it will be noted, in FIGURES 1 and 4, that the page loader is provided as a helically coiled wire in the general shape of a spring. However, the page loader 20 does not function as a spring and the coils of wire are preferably of low-spring tension to permit easy separation thereof and to prevent binding of the pages of a book. The coil 20 is mounted on an upright rotatable shaft 84 by means of inserting the ends 86, 88 of the coil through openings in the shaft 84. An inner shaft may be provided within the shaft 84 having openings therethrough registering with the shaft 84 openings and the structure may subsequently be tightened by nut 90 to clinch the coil ends in place.

An annular support element 92 is provided beneath the coil 20 and is held in place by a bushing 94 and the coil end 88.

As shown in FIGURE 4, each page 96 of the book 98 which is to be turned is inserted between two of the coils of the helical wound wire 20, with the page to be first turned resting on top of the coil. Upon rotation of the coil, each page will successively be fed to the top of the coil for turning. Loading of the coil is accomplished by first positioning the pages of the book 98 which are not to be turned beneath the annular element 92. The pages to be turned are then laid one by one, on top of the coil and the coil is rotated 360° counterclockwise for each page to thus feed the pages downwardly as will be more fully explained hereinafter.

The page turning arm 22 comprises a wire element having one end portion 100 adjacent to the coil end 86 and at the same horizontal level as the end 86. The end portion 100 is inserted into the opening in the shaft 84. Extending from the end portion 100 is a curved portion 102 which projects towards the side element 24 of the support. The portion 102 is inclined upwardly from the horizontal to facilitate moving a page upwardly during the page turning operation. The portion 102 terminates in an upwardly extending portion 104 which forms a notch for engaging the edge of a page. A straight portion 105 extends from the portion 104 into engagement with an opening in the shaft 84.

The method of turning a page is shown in FIGURES 2 and 3. The shaft 84 is rotated by the power means within the casing 18 to rotate both the coil 20 and arm 22 clockwise. The page 96 lying on top of the coil 20, being at the same level as the end portion 100 of the arm, will pass over this portion of the arm as the arm swings towards the page as shown in FIGURE 2. As the arm continues to rotate, the page will be lifted by the curved portion 102 until engaged by the portion 104. At this point, continued rotation of the arm 22 will move the page to the other side of the book where it will fall in place thus exposing a new set of pages to the viewer. The arm 22,

5 after turning a page, is stopped and is in position to turn another page. Preferably, the outer end of the arm is positioned over the page which has been turned to act as a stop to prevent the page being blown back to its original position. The coil 20, which is also rotated along with the arm 22, will feed a new page to the top thereof upon each complete rotation of the shaft 84 in position for the next turning operation.

10 As previously mentioned, loading of the coil 20 with pages to be turned is accomplished by placing each page, one at a time, on top of the coil 20 and then rotating the coil 20 in a direction to feed the pages downwardly in the coil. Turning of the coil is accomplished manually by grasping the arm 22 and turning it causing rotation of the shaft 84 and coil 20. The upwardly slanting portion 102 of the arm will first pass over the page and as the arm is turned, the portion 100 will contact the upper surface of the page and hold the page in a position where the end portion 86 of the coil will pass over the page thus causing the edge of the page to be positioned between the first and second turns of the coil. Subsequent rotation of the coil will thus cause the page to be fed downwardly to thus prepare the coil for loading of another page therein. The page by page loading is continued 15 until all of the desired pages have been loaded into the coil.

20 It will be appreciated that the structure thus far described may be varied from that illustrated within the scope of the invention. For example, the arm 22 may be provided as a member formed from a sheet of metal or other material rather than as a wire element. A cylinder having a helical groove formed therein may be substituted for the helical wire coil 20. Similarly, the book support 12 may be formed from sheet material rather than from wire as shown.

25 Referring now to the drive system for the shaft 84, it will be noted that the casing 18 is mounted for vertical adjustment on the support 12 as shown in FIGURE 6. A bracket 103 having inturned portions in engagement with spaced apart wire elements 48, 110 is adjustably secured to the casing back wall 112 by nut and bolt structures 114, 116. This arrangement permits vertical adjustment of the coil 20 so that different book thicknesses may be inserted beneath the annular element 92.

30 40 45 Mounted within the casing 18 is an electric motor 118 which is connected through a pulley system to a shaft 120. The shaft 120 is in turn drivingly connected to the shaft 84. As will be noted in FIGURE 6, the output shaft 122 of the motor engages a belt 124 which in turn engages a large pulley 126 which is fixedly mounted on shaft 128. The shaft 128 carries a set of small pulleys 130, 132 which engage belts 134, 136. The belts 134, 136 in turn engage a set of pulleys 138, 140 which are fixedly mounted on the shaft 120 to thus complete the drive from the motor 118 to the shaft 120. As will be noted from the respective sizes of the pulleys, there is a considerable speed reduction from the output shaft of the motor 118 to the shaft 120. This results in the shaft being driven at a relatively slow speed while the motor may operate at a relatively high speed.

50 55 60 65 70 Referring to FIGURE 5, it will be seen that power is supplied to the motor 118 through a single pole, double throw switch 142. The switch 142 is preferably a foot switch as shown in FIGURE 1 of the push-push type wherein each depression of the switch plunger 144 throws the contact arm 146 to alternate contacts 148, 150. The switch pole 152 is connected by lead 154 to one side of A.C. power 156. The other side of power is connected directly to one side of the motor by lead 158. One lead 160 extends from the contact 148 to a post 162 while the contact 150 is connected to a second post 164 by lead 166. A second pair of posts 168, 170 is provided and leads 172, 174 extend from these posts and are connected in parallel to form a single lead 176 which is connected to the motor 118. A spring switch arm 178, 180 extends

form each post 168, 170 towards one of the posts 162, 164. The arms 178, 180 are bent so that they normally spring a short distance away from the posts 162, 164 and must be forced into contact therewith. A cam 182 is provided to alternately force one of the arms 178, 180 into contact with its respective posts 162, 164 to permit completion by the switch 142 of a circuit through the motor 118.

The cam 182 has two lobes 184, 186 which are spaced 180° apart with respect to the center of the shaft 188 upon which the cam is fixedly mounted. The cam is also provided with a pair of diametrically opposed flats 190, 192 which are also spaced 180° apart.

With the cam in the position shown in FIGURE 5, the lobe 184 depresses the switch arm 178 to complete a circuit through posts 162, 168. With the switch arm 146 making contact with the contact 148 as shown in solid lines, a circuit is completed through the motor 118. However, if the cam 182 is rotated a distance of 90°, the lobe 184 will pass by the arm 178 and the flat 190 will permit the arm to spring outwardly from post 162 to break the above-mentioned circuit to the motor. When the cam is so rotated, however, the lobe 184 will force the second arm 180 into contact with the post 164, thus permitting a second circuit to be made through the motor 118 when the switch arm 146 is moved to the dotted line position to make contact with the contact 150.

Means are illustrated in FIGURE 7 for rotating the cam 182 through an arc of 90° upon each complete 360° rotation of the shaft 120. As will be noted, the cam shaft 188 extends through the wall 194 in which it is journaled. A pinwheel 196 having four arms 198 spaced at 90° intervals is also fixedly mounted on the shaft 188. The arms 198 are in the path of an arm 200 which is secured to the shaft 120. Upon each revolution of the shaft 120 in the direction of arrow 202, the arm 200 will contact one of the pinwheel arms 198 and rotate the pinwheel and cam shaft 188 through an arc of 90°. Thus the cam 182 will be rotated 90° upon each complete rotation of the shaft 120.

As previously explained when the cam rotates 90°, whatever circuit was previously made through the motor 118 will be opened, thus cutting off power to the motor. The motor will thus stop after each single rotation of the shaft 120. It has been found that the pulley system between the motor and shaft operates as an effective brake to the motor to cause the motor to stop at substantially the end of each single rotation of the shaft.

It will be appreciated, of course, that a single rotation of the shaft 120 will cause a single revolution of the coil 20 and arm 22 to thus turn one page of the book mounted on the book support 12. The next page is turned by depressing switch plunger 144 to close the second circuit through the motor 118. This process is continued until all of the pages have been turned.

It will be noted in FIGURE 7 that the arm 200 comprises a channel member 204 which is secured to the shaft 120 by a band 206. A second channel member 208 is hingedly mounted on member 204 by a pin 210. The member 208 can pivot forwardly towards the pinwheel as viewed in FIGURE 7 but is stopped from pivoting in the reverse direction by the member 204. When the shaft 120 is rotated in the reverse direction from arrow 202, the member 208 upon contacting one of the pinwheel arms 198 will pivot out of engagement therewith without moving the pinwheel. This permits the shaft 120 to be turned during loading of the coil 20 without rotating the pinwheel 196. Such rotation would close a circuit through the motor 118 and cause the motor to rotate the shaft 120 one revolution.

Having thus described our invention, we claim:

1. A device for turning the pages of a book comprising a book support for receiving a book in open position, a rotatable wire helix for receiving between each pair of coils thereof the edge of a page of a book positioned on the book support, said helix being adjustably mounted on the book support for adjustment in directions substantially perpendicular to the plane of a book positioned thereon whereby the helix is positionable above the pages which are not to be turned, a rotatable arm having one end positioned at, and even with, the end surface of the helix which is remote from the book support, said arm being in the form of a wire loop having a relatively large diameter to form a support surface for the page of a book, said loop having an upwardly directed portion at its outermost terminus for lifting the edge of a page, and power means to rotate the helix and the arm to feed pages to said remote end surface of the helix for engagement and turning by said arm.
2. A device for turning the pages of a book comprising a book support for receiving a book in open position, a rotatable wire helix for receiving between each pair of turns thereof the edge of a page of a book positioned on the book support, said helix being mounted on the support adjacent to the pages to be turned, a rotatable arm in the form of a wire loop, said loop having a relatively large diameter to form a support surface for the page of a book, one end of said loop being positioned at, and even with, the end surface of the wire helix remote from the book support, said loop having an elongated curved portion extending away from the helix and inclined away from the plane of the book support, said curved portion terminating in an upwardly directed portion for lifting the edge of a page, and power means to rotate the helix and the arm to feed pages to said remote helix end surface for engagement and turning by said arm.
3. A device for turning the pages of a book comprising a book support for receiving a book in open position, a shaft, a wire helix mounted on said shaft for receiving between each pair of turns thereof the edge of a page of a book positioned on the book support, said helix being mounted on the support adjacent to the pages to be turned, a loop having one end secured to the shaft, said loop having a relatively large diameter to form a support surface for the page of a book, said end being positioned at, and even with, the end surface of the wire helix remote from the book support, said loop having an elongated curved portion extending away from the helix and inclined away from the plane of the book support, said curved portion terminating in an upwardly directed portion for lifting the edge of a page, and another portion of the loop extending from the upwardly directed portion back to the shaft into securement therewith, and power means to rotate the shaft to thereby rotate the helix and loop to feed pages to said remote helix end surface for engagement and turning by said loop.
